SHUTTLELESS LOOM

Henry Dreyfus, London, William Alexander Dickie and Frank Corbyn Hale, Spondon, near Derby, England, assignors to Celanese Corporation of America, a corporation of Delaware

Application November 12, 1930, Serial No. 495,139
In Great Britain December 9, 1929

5 Claims. (Cl. 139—126)

This invention relates to shuttleless looms, that is, looms in which weft is inserted from the stationary supply instead of from a shuttle. The invention relates more particularly to the weaving in shuttleless looms of fabric in which the weft is laid as a single pick, one end of the weft being turned into the fabric to form a selvedge. This turning in of the weft may be effected by inserting the weft as a double loop, one end of which remains attached to the preceding pick inserted from the same side of the loom, and by severing the connection of the weft to such preceding pick at some distance inside the edge of the fabric when the double loop has been carried approximately half way through the shed. One limb of the loop is, of course, still connected to the yarn supply, and the other limb of the loop, i. e. the one which has just been severed, is carried through the remaining part of the shed. Previously, this method of weft insertion has been performed by positively actuated means which in some cases effect the transfer of the weft loop half way through the shed to withdrawing means also positively actuated to carry the severed limb of the loop through the rest of the shed, a cutting device being operated by suitable gearing to sever the weft on the arrival of the weft-inserting means half-way through the shed. A similar mode of weft insertion combined with the formation of a turned-in selvedge is carried out in a shuttleless loom according to the invention in which the weft is introduced into the shed by a dummy shuttle, in the form of a loop connected to a previous pick, and the passage of the shuttle through the shed causes the operation of cutting means which sever one end of the weft loop from the preceding pick at the time when the loop length is just sufficient for the single pick. Preferably the cutting means are put into operation by the closing of an electric circuit by the shuttle at some point in its passage through the shed, there being included in the circuit an electro-magnet or solenoid operatively connected with the cutting means. Any suitable type of electric contacts may be mounted on the reed or shuttle race, one or both of the contacts preferably being adjustable in position so that the length of the pick laid may be regulated. A convenient form of contact may be provided by including one or other desired number of the reed dents in the electric circuit, the separate dents being of course, insulated from each other. By making connection with appropriate dents severing of the weft can be made to take place at any desired time during the passage of the shuttle.

The length of the weft laid may be somewhat longer than the width of the fabric, so that a short amount of weft projects from the side of the fabric opposite to that at which the weft was inserted and this short amount may be turned round one or more warp threads on that edge of the fabric or turned into the succeeding pick, any suitable means being employed for this purpose.

It will be understood that it is desirable for the dummy shuttle to introduce weft from both sides of the loom in order to obtain the greatest possible output, and therefore, a cutting device may be disposed at each side of the loom, each cutting device being actuated in the manner above described by the passage of the shuttle in either direction through the shed. The same or a different set of contacts may be employed for closing the two cutting device circuits. In the case where one set of contacts is employed, a switch may be included in and actuated by each circuit and closed by mechanism driven by any suitable part of the loom to provide that only the cutting device appropriate to the side of the loom from which weft is being supplied is actuated when the shuttle completes the circuit through the set of contacts. Alternatively, entirely independent circuits may be employed, together, if desired, with means for ensuring the actuation of only one cutting device at a time, in the manner described above. A further means for securing this result consists in arranging for the cutting devices in turn to be withdrawn completely from operative position during the pick in which they are not required to operate, any suitable mechanism being employed for the purpose.

One form of loom according to the invention will now be described with reference to the accompanying drawing, but it is to be understood that the following description is given by way of example only and is in no way limitative.

Fig. 1 is a diagrammatic front elevation of the slay and reed of a loom together with a weft severing mechanism and electrical operating mechanism;

Fig. 2 is an end elevation of a weft severing device and mounting and positioning mechanism for the same; and

Fig. 3 is an end elevation of a weft severing device to an increased scale.

Fig. 4 is a diagrammatic view showing the dummy shuttle in mid-shed position.

Fig. 5 is a similar view, after the loop 38 has been severed and the dummy shuttle has completed its movement through the shed.

119

Referring to Figs. 1 and 2, a dummy shuttle weft carrier 5 is provided with a short metal plate 6 on the side next to the reed and is picked across the shuttle race 7 of the loom by any suitable form 5 of picking mechanism (not shown). The metal plate 6 is secured to a recess in the shuttle wall flush with the surface of the wall.

The shuttle 5 bears lightly against the reed 8 as it passes across the race so that the plate 6 10 makes sliding contact with the dents 9' on the reed 8. At some distance from each end of the reed a number of reed dents 9' are provided at their upper ends with connecting lugs. The lugs on one side of the dents 9' are coupled to a lead 15 11 connected to the low tension side of a transformer 12. The lead 11 is also connected to one winding 13 of a double wound solenoid 14 which winding 13 is in turn connected to the other pole of the low tension side of the transformer, or with 20 the secondary low tension current which is always flowing in the winding 13.

A further number of reed dents 9'' alternating with the dents 9' are provided at their lower ends with connecting lugs and the lugs of one side of 25 dents are coupled by a lead 16 to one side of the second winding 17 of the solenoid 14, and the other end of the winding 17 is connected to the second pole of the low tension side of the transformer. Current can always flow in the winding 30 17 by contact being established between the alternating sets of dents 9' and 9'' by the passage of the shuttle across the reed.

A separate circuit for the second sets of dents 9', 9'' may be provided by the leads 110, 160 in 35 parallel with the circuit of the first sets or the lugs of the second sets of dents may be coupled directly to the leads 11, 16 of the first set.

Closure of the circuit through the winding 17 by passage of the shuttle across the race, operates 40 the plunger 15 of the solenoid 14 to close the circuit of the two solenoids 20 which are connected in parallel to the leads 18, 19 on the transformer 12. A spring arm 22, carried by a contact block 21 and having a contact 23 adapted to engage a 45 block 24 in the main lead of the solenoid circuits, is operated through a lever 25 by movement of the plunger 15. The two windings 13 and 17 of the solenoid 14 are wound in opposite directions so that when current is passed through both on 50 the closure of the circuit the solenoid 14 is de-energized and the plunger 15 is free to move to allow the spring loaded arm 22 to rise and close the circuits of the solenoids 20. When the shuttle has passed the contact on the reed only the winding 55 13 on the solenoid 12 is operative, so that the plunger is drawn inwards to cause the lever 25 to move the arm 22 to the other position and re-open the circuits of the solenoids 20.

Closure of the circuits passing through the 60 solenoids 20 operates weft severing devices as will now be described.

Each weft severing device comprises a moving knife blade 28 pivotally mounted on a fixed blade 29, and is carried by a reciprocating member 30 65 which slides in a bracket attached to the frame of the loom, and the reciprocation of the members 30 is effected in such a manner that one of the severing devices passes between the warps near to one side of the fabric to engage a weft 70 thread which has been inserted by the shuttle 5 from that side of the fabric.

The reciprocating motion of each member 30 is obtained from a cam 31 on the half time shaft of 75 the loom, which cam 31 bears against a cam 34 on a spring-loaded pivotally mounted arm

35 which is connected to the lower end of the sliding member 30. On the passage of a severing device between the warps, the knife blade 28 is retained in the open position by means of a spring 32, so that the severing device engages the weft 80 thread but allows it to pass there-through until severance is to be effected.

When the member 30 has been raised to its highest position, an abutment 27 at the lower end 85 of the pivotally mounted blade 28 is opposite the plunger 26 of the solenoid 20, so that outward movement of this plunger on closure of the solenoid circuit causes it to engage the abutment 27 and close the blade 28 against the fixed blade 29.

Referring now to Fig. 2 the full lines show the 90 knife 28 open and the arm 35 in its lower position, and the dotted lines show the knife closed and raised to its upper position. Fig. 3 shows the 95 severing device to a greater scale with the knife 28 open and the device at its lower position. The cam 31 is provided with a steep lift to pass the 100 severing device quickly between the warps. The severing device is withdrawn quickly after cutting of the weft so as to be clear of the slay during beat-up.

It will be understood that while both solenoids are energized simultaneously by closure of the circuit of the solenoid 14 through the reed dents 9', 9'', only one of the severing devices is in operative position at any one time. The actual time 105 at which severing of the weft takes place is determined by the distance of the dents 9', 9'' included in the circuit from the ends of the reed. Thus, on insertion from the left-hand side of the loom, cutting takes place when contact is established 110 across the left-hand sets of dents 9', 9'' or vice versa.

The operation of the apparatus will now be described with reference to Figs. 4 and 5.

Weft is supplied from bobbins 36 situated at 115 each side of the loom and is presented to the path of the dummy shuttle 5 so as to be carried into the shed in the form of a loop 38, which is shown proceeding from the left hand bobbin 36 in Fig. 4. The loop 38 is connected to the previous pick 120 of weft 37 which has been inserted from that side of the loom and has been followed by a pick from the other side.

In Fig. 5 the loop 38 has been severed from the 125 previous pick 37, and has been carried through the shed by the passage of the shuttle 5. It will be seen that a small length of weft is left in the shed extending from the edge of the fabric to the point of severing, and that this short length 130 of weft will be beaten up with the length of weft now extending across the shed from the bobbin 36.

In each figure a portion of the woven fabric is 135 illustrated which shows clearly the manner in which the picks of weft are laid, and secured in the selvedge.

What we claim and desire to secure by Letters Patent is:—

1. A shuttleless loom in which weft is inserted in the shed by a dummy shuttle in the form of a 140 loop connected to a preceding pick, said loom comprising means for severing weft inserted by the dummy shuttle, and control means on the loom reed in connection with said severing means, said control means on the reed being adapted to 145 be engaged by the dummy shuttle in its passage across the reed the construction and arrangement being such that engagement of the dummy shuttle therewith causes actuation of the severing means when the loop drawn by the dummy shut- 150

- tile has reached a length from the point of severance sufficient to complete the pick. 80
2. A shuttleless loom in which weft is inserted in the shed by a dummy shuttle in the form of a loop connected to a preceding pick, said loom comprising electrically-operated means for severing weft inserted by the dummy shuttle and control means on the loom reed in connection with said severing means, said control means being adapted for engagement by the dummy shuttle on its passage across the reed so as to effect closure of the severing means circuit when the weft loop has reached a length from the point of severance sufficient to complete the pick. 85
- 15 3. A shuttleless loom in which weft is introduced into the shed by a dummy shuttle in the form of a loop connected to a preceding pick, said loom comprising electrically-operated means for severing weft inserted by the dummy shuttle, electrical contacts on the loom reed, a low-tension circuit including said contacts, means on said shuttle adapted to connect said reed contacts together in the passage of the shuttle across the reed, and a high-tension circuit operated by said 90 low-tension circuit adapted to actuate said weft-severing means on connection of said reed contacts so that the weft is severed from the preceding pick when the loop has reached a length from the point of severance sufficient to complete the pick. 95
- 20 4. A shuttleless loom in which weft is inserted in the shed by a dummy shuttle in the form of a loop connected to a preceding pick, said loom comprising weft-severing means arranged at a point some distance inside the edge of the fabric adapted to sever weft inserted by the dummy shuttle, control means on the loom reed in connection with said severing means, said control means on the reed being adapted to be engaged by the dummy shuttle in its passage across the reed, the construction and arrangement being such that engagement of the dummy shuttle therewith causes actuation of the severing means when the loop drawn by the dummy shuttle has reached a length from the point of severance sufficient to complete the pick. 100
- 25 5. A shuttleless loom in which weft is inserted in the shed by a dummy shuttle in the form of a loop connected to a preceding pick, said loom comprising weft-severing means arranged at each side of the loom adapted to sever weft inserted by the dummy shuttle, control means on the loom reed in connection with said severing means, said control means on the reed being adapted to be engaged by the dummy shuttle in its passage across the reed from either side of the loom, the construction and arrangement being such that engagement of the dummy shuttle therewith causes actuation of the severing means when the loop drawn by the dummy shuttle has reached a length from the point of severance sufficient to complete the pick. 105
